OVEN HEAT CONTROL

Theodore A. Wetzel, Milwaukee, Wis., assignor to Milwaukee Gas Specialty Company, Milwaukee, Wis., a corporation of Wisconsin

Application April 9, 1938, Serial No. 201,085

1 Claim. (Cl. 158—117.1)

This invention relates generally to control mechanism and is more particularly concerned with controlling mechanisms that include thermostatically responsive contacts disposed in or adjacent a heated zone, such as a gas flame, or the like.

A feature of this invention is the provision of controlling mechanism, especially arranged for use in domestic gas ranges but not necessarily limited thereto, in which an electric shut-off valve is controlled by means that includes hermetically sealed non-liquid contacts which are disposed in thermal relation with either the pilot burner or the main burner of the gas range. It is a further feature of this invention to provide hermetically sealed electrical contacts of the non-liquid type disposed in or adjacent the flame of either a pilot burner or a main burner and operative to control an ignition circuit in the gas range or other appliance.

Another feature of this invention lies in the provision of controlling mechanism that embodies means that turns on ignition means and opens a shut-off valve to permit gas or other fuel to flow through a burner and in which a hermetically sealed thermostat holds the shut-off valve open and shuts off the ignition circuit if the main burner is ignited properly but in which if the main burner does not ignite a thermostatic unit closes the shut-off valve so that no further gas or other fuel can flow to the system.

These and other objects and advantages of the present invention will be apparent to those skilled in the art after a consideration of the following detailed description, taken in conjunction with the accompanying drawing illustrating the preferred physical embodiments of the invention.

In the drawing:

Figure 1 is a view showing a domestic gas range incorporating the principles of the present invention; and

Figure 2 is a detail sectional view of the thermostatically responsive switch associated with the burners as shown in Figure 1.

While I shall describe my invention as incorporated in controlling mechanism for a domestic gas range, it is to be understood that this is only for purposes of illustration and that my invention is equally applicable to controls for other appliances and devices.

Referring now more particularly to Figure 1, the gas range 1 is provided with a plurality of open top or grate burners 2 of usual construction and an oven compartment indicated in its en-

5 tirety by the reference numeral 3. The oven has an oven burner 6 in the lower portion thereof of generally conventional construction, and gas is supplied to the burner 6 from a gas supply pipe 8 and an inlet conduit 10. The flow of gas to the burner is under the control of an oven thermostat 12, which includes an adjustable valve 13 and suitable thermostatically controlled mechanism that includes a thermostatic bulb 15 located in 10 the upper part of the oven 3. The control of the gas flow may be adjusted by suitable mechanism that includes a knob 17 disposed at the front of the range 1.

15 Referring now to Figure 2, a thermal switch unit 31^a is enclosed in a sealed casing 70, within which are mounted contact members 65, 66 and 67. The members 65 and 67 have contacts 72 and 73 secured thereto. The intermediate member 66 has two contacts 74 and 75. A bimetallic 20 element 71 is disposed between the members 66 and 67, and the entire assembly with the required insulating blocks and the like is mounted on a pair of spring arms 78 and 79. The unit 31^a is so arranged that when the thermostat 71 is cold 25 the contacts 75 and 73 on the members 66 and 67 are in engagement and the contacts 72 and 74 on the members 65 and 66 are out of engagement.

In Figure 1 pilot 81, which is in the nature of a 30 stand-by pilot, is connected by a conduit 82 to the gas inlet conduit 10 that is connected to the main 8. The pilot 81 is disposed at a position adjacent the control valve 12. The thermostat switch 31^a is mounted adjacent the pilot 81 in order that a constant flame of the latter impinges on the shield or casing thereof.

The thermostatic switch 31^a is embodied in an 35 ignition circuit which includes an ignition coil 85, the transformer T, a heat responsive switch 40 unit 86 and a shut-off valve structure 52^a that includes two coils 87 and 88, both acting on a plunger 90 that controls a valve 91 which, in turn, controls the flow of gas to both the main burner 6 and the pilot burner 81.

45 The heat controlled thermostat switch 86 embodies a housing 93 containing a switch assembly, the latter including a bimetallic element 92 connected to a fixed part, as at 92^a, on the housing 93 and is disposed between a pair of spring contacts 94 and 95 having contact points 97 and 98, respectively. Suitable insulating blocks 100 serve to mount the ends of the spring members 94 and 95 opposite the contacts 97 and 98 so that the members 94 and 95 are biased for movement toward one another. A heating resistance 102 is

disposed within the housing 93 in a position to affect the bimetallic element 92. Normally, when the element 92 is cold, it moves to a position holding the spring member 94 with its contact 97 out of engagement with the contact 98 on the other member 95, but the latter is held against upward movement by a fixed stop 104. Thus, when no current flows through the resistance element 102, the thermostat 92 is cold and the contacts 97 and 98 are open.

The oven control switch 50 is connected by a conductor 110 to one side of the transformer T. The other end of the latter is connected by a conductor 111 to the fixed end 112 of the spring member 94, and at this point the intermediate conductor 58 of the unit 31^a is also connected. The conductor 59 of the unit 31^a is connected to one side of the ignition coil 85, and another conductor 115 connects the other end of the ignition coil 85 to one end of the resistance unit 102. The other end of the latter is connected by a conductor 116 to the oven switch 50, and at an intermediate point the conductor 116 is connected by means of a conductor 118 to the adjacent ends of both of the coils 87 and 88. The other end of the first coil 87 is connected to the lead 57 of the unit 31^a, and the other end of the coil 88 is connected by a conductor 119 to the outer end of the other spring member 95, as at 121, of the unit 86.

The electric shut-off valve 52^a is so constructed that the coil 88 can exert sufficient pull to raise the valve 91 into its open position, permitting gas to flow from the main 8 to the control unit 12, but the coil 87 is constructed so that it is capable only of holding the valve 91 open provided the valve is already in its open position when the coil 87 is energized, but the coil 87 is not capable of exerting sufficient pull to open the valve if it should be closed when the coil 87 is energized.

The operation of the electrical ignition system in which the unit 31^a is incorporated, according to the principles of the present invention, is substantially as follows:

When it is desired to turn on the oven of the range 1, the oven switch 50 is closed. Current then flows from one side of the secondary of the transformer T through the conductor 110, the closed switch 50, the conductor 116, the heating resistance 102, the conductor 115, the ignition coil 85, the lead 59, the member 67 (Figure 2), the engaged contacts 73, 75 (since the unit 31^a is cold), the member 66, the lead 58, and the conductor 111 back to the other side of the secondary of the transformer T. This flow of current heats the ignition coil 85 and the resistance coil 102, and heat from the latter affects the thermostat 92 so that after a short period of time it bends downwardly and permits the contact 97 on the spring member 94 to engage the contact 98 on the other spring member 95. As soon as the contacts 97 and 98 are engaged current flows from one side of the secondary of the transformer T through the conductor 110, the closed switch 50, the conductor 118, the solenoid coil 88, the conductor 119, the spring member 95, the engaged contacts 98 and 97, the spring member 94, and the conductor 111 back to the other side of the transformer. This flow of current energizes the solenoid coil 88 and opens the valve 91, permitting gas to flow from the main 8 to the inlet connection 10 and the regulating valve 12 to the main gas burner 6. Since at this time the ignition coil 85 is hot, gas flowing out of the burner 6 normally is ignited and the burner flame in turn ignites the

flow of gas to the stand-by pilot 81. The pilot flame from the pilot burner 81 then heats the unit 31^a causing thermostat 71 to engage the contact 74 with the contact 72 and then disengage the contact 75 from the contact 73. This interrupts the current flowing through the ignition coil 85 and the heating coil 102, and energizes the holding solenoid coil 87 through the following circuit: From one side of the secondary of the transformer T through the conductor 110, the closed switch 50, the conductor 118, the coil 87, the lead 57, the member 65, the engaged contacts 72 and 74, the member 66, the lead 58, and the conductor 111 back to the other side of the transformer. Since current through the resistance 102 is interrupted the element 91 cools and returns to a position separating the contacts 97 and 98, whereupon the coil 88 is deenergized.

In the event, however, that after the initial energization of the circuit, including the ignition coil 85, the heating coil 102 and the solenoid coil 88, the main burner 6 or the pilot 81 does not ignite, then the unit 31^a remains in its cold position and current continues to flow through the first-mentioned circuit above. The continued flow of current through the heating coil 102 continues to heat the thermostat 92 so that the thermostat 92 will be bent downwardly and will eventually leave the spring member 94 against the stop 104 and will move the lower spring member 95 away from the stop 104 and disengage the contacts 97 and 98. As soon as this disengagement occurs the current through the solenoid opening coil 88 is interrupted and the shut-off valve 91 automatically returns to a closed position, even though the oven switch 50 should be left closed. Thus, the user will know from the fact that the burner does not ignite that something is wrong with the system, but the automatic closing of the shut-off valve prevents filling the oven with unburned combustible gas.

Another advantage of this arrangement is that there is no constantly burning pilot flame, with attendant possibility that the pilot might go out and fill the space with combustible gas. As soon as the oven switch is closed, the ignition coil is heated, but if the burner does not light then the system automatically closes the shut-off valve so that only a very small quantity of gas flows into the zone during the time that the shut-off valve was temporarily opened to provide an opportunity for the burner to become lighted. In a similar way, if the pilot 81 does not light, the unit 31^a is not energized even though the burner 6 might light. If the stand-by pilot does not light or should go out, then the unit 31^a returns to its cold position and the subsequent continued heating of the coil 102 that follows the closing of the cold contacts in the unit 31^a will act through the thermostat or bimetallic element 91 to close the shut-off valve automatically, preventing further gas flow. Also, any interruption of current, as by a failure of the supply, even if only momentary, or a rapid turning off and on of the oven switch 50, automatically causes the system to shut down, and when the current is restored the system automatically starts a new ignition cycle.

It will thus be seen that the arrangement shown in Figure 1 employing the sealed or shielded thermostatically controlled contacts of the non-liquid type is so arranged that, without a constantly burning pilot flame and the attendant possibility of going out and filling the oven space with unburned combustible gas, the oven

can be turned on merely by closing the oven control switch 50, which energizes an ignition coil and when the latter is at a temperature sufficient to ignite gas the shut-off valve is opened to admit gas to the burner, but if for some reason the burner does not light then after a moment or two the gas is automatically turned off and at the same time current to the ignition coil is also automatically interrupted. Also, the oven, when on, can be turned off merely by opening switch 50 which, in the normal operation of the oven control means, is effective at all times for controlling opening and closing of the shut-off valve 91.

While I have described the preferred means in which the principles of the present invention have been embodied, it is to be understood that my invention is not to be limited to the particular details shown and described above, but that, in fact, widely different means may be employed in the practice of the broader aspects of my invention, within the scope of the appended claim.

What I claim, therefore, and desire to secure by Letters Patent is:

In combination in oven control means, an oven, a main burner therein, a gas supply line connected to said main burner, a pilot burner adjacent said main burner connected to said line, a normally closed shut-off valve in said line in advance of said burners, a first solenoid coil effec-

tive when energized for opening said valve, a second solenoid coil effective when energized for holding said valve open but ineffective for opening it, an ignition coil adjacent said main burner, a transformer, a manually operable control switch having one side connected to one end of the secondary winding of said transformer, a heating coil connected to the other side of said switch and to one side of said ignition coil in series, one end of each of said solenoid coils being connected to said other side of said switch, means comprising thermostatic means subject to the heat of said burners effective for closing the circuit of said ignition coil and opening the circuit of said second solenoid coil when said thermostatic means is cold and opening the circuit of said ignition coil and closing the circuit of said second solenoid coil when said thermostatic means is hot, when said manually operated switch is closed, a normally open time switch connected to the other end of said first solenoid coil and to said other end of said secondary winding in series therewith, and a thermostat exposed to said heating coil effective for closing said time switch responsive to heating of said heating coil for a predetermined time and for opening said time switch responsive to heating of said heating coil in excess of said predetermined time.
